(57) **CLAIM**

I claim the ornamental design for a sequencing instrument display screen or portion thereof with graphical user interface icon, as shown and described.

DESCRIPTION

This patent contains at least one drawing executed in color. Copies of this patent with a color drawing will be provided by the Office upon request and payment of the necessary fee. FIG. 1 depicts a front view of a sequencing instrument display screen or portion thereof with graphical user interface icon showing a first embodiment of the design; and, FIG. 2 depicts a front view of a sequencing instrument display screen or portion thereof with graphical user interface icon showing a second embodiment of the design. The broken lines illustrate a display screen and form no part of the claimed design.
